CLAIM

The ornamental design for a face plate for a video game controller, as shown and described.

DESCRIPTION

FIG. 1 is a top perspective view of a face plate for a video game controller showing our new design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof; and,

FIG. 9 is a top perspective view of the face plate for a video game controller in environment of use.

In the drawings, the broken lines showing of the portions of the face plate for a video game controller form no part of the claimed design. The broken lines in FIG. 9 showing the body of the video game controller and controller inputs illustrate environmental structure that form no part of the claimed design.
